CARPET.

No. 17,662.

Patented Aug. 23, 1887.

UNITED STATES PATENT OFFICE.

WILLIAM E. SAYERS, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 17,662, dated August 23, 1887.

Application filed July 21, 1887. Serial No. 244,938. Term of patent 3½ years.

To all whom it may concern:

Be it known that I, WILLIAM E. SAYERS, of New York city, in the county and State of New York, have invented a new and original Design 5 for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is composed of a variety of circular flower forms, varying in size and orna-

mentation, irregularly grouped or disposed over the face of the carpet. Some of the larger flower forms have a central circular portion 20 with a row of small figures around the edge of the same. Some of the flower forms are composed of a mass of radial arms or leaves. Others have their edges indented regularly entirely around their circumference. 25

What I claim as new, and desire to secure by Letters Patent, is—

The design for carpets, consisting of the design substantially as shown.

W. E. SAYERS.
